[57] CLAIM

The ornamental design for a combined back massager and control, as shown.

DESCRIPTION

FIG. 1 is a perspective view of a combined back massager and control, showing our new design;

FIG. 2 is a rear elevation of the back massager without the control;

FIG. 3 is a front elevation thereof;

FIG. 4 is a top plan view thereof;

FIG. 5 is a bottom plan view thereof;

FIG. 6 is a left end elevation thereof;

FIG. 7 is a right end elevation thereof;

FIG. 8 is an enlarged top plan view of the control;

FIG. 9 is a bottom plan view thereof;

FIG. 10 is a left side elevation thereof;

FIG. 11 is a right side elevational thereof;

FIG. 12 is a lower end elevation thereof; and,

FIG. 13 is a top end elevation thereof.

The broken line showing of the cord in FIGS. 1-3, 8 and 9 is for illustrative purposes only and forms no part of the claimed design.
